D. F. FESLER

DEMONSTRATION APPARATUS

Filed May 24, 1922

Patented Mar. 4, 1924.

1,485,841

UNITED STATES PATENT OFFICE.

DOUGLAS F. FESLER, OF CHICAGO, ILLINOIS, ASSIGNOR TO THE BASSICK MANUFACTURING CO., OF CHICAGO, ILLINOIS, A CORPORATION OF DELAWARE.

DEMONSTRATION APPARATUS.

Application filed May 24, 1922. Serial No. 563,196.

To all whom it may concern:

Be it known that I, DOUGLAS F. FESLER, a citizen of the United States, and resident of Chicago, in the county of Cook and State of Illinois, have invented certain new and useful Improvements in Demonstration Apparatus, of which the following is a full, clear, concise, and exact description, reference being had to the accompanying drawings, forming a part of this specification.

My invention relates to improvements in demonstration apparatus, and is particularly concerned with the provision of a novel demonstration apparatus to be used for demonstrating the utility and mode of operation of lubricating covers for vehicle springs.

While I have illustrated my apparatus as comprising means for demonstrating spring covers of the type illustrated in Patents, Numbers 1,235,211 and 1,319,349, issued to Benno B. Leustig, July 31, 1917, and October 21, 1919, respectively, it is to be understood that my invention is not limited to this particular use.

The objects of my invention are to provide a demonstration apparatus of the character described which is simple in construction, economical to manufacture, and which can be operated continuously over extended periods of time without requiring the attention of an operator.

Other objects will appear as this description progresses, reference being had to the accompanying drawings, in which—

Figure 1 illustrates a preferred embodiment of my invention shown in plan, certain portions of the spring cover and the container for the operating mechanism being broken away for the purpose of better illustration, and

Figure 2 is a side elevation thereof, portions of the container being broken away to reveal the details of construction of the operating mechanism.

In both views, similar reference characters will be used for referring to similar parts.

My improved demonstrating apparatus comprises a container having the top wall 5 and the bottom wall 6, each of which, as indicated in Figure 1, is enlarged at one end to provide a housing for the driving mechanism which will be described in detail later on. Suitable side walls 7, 7₁ and 8, and the two end walls 9 and 10 complete the container.

A post 11 is secured to the end wall 9 by means of screws 12, and extends upwardly beyond the top wall 5, as shown in Figure 2. A block 13 is secured to the post 11 by means of screws 14, and to this block 13 is secured the larger open end of the spring cover which is illustrated as a whole by reference character 15. For this purpose, I prefer to use the two clamping plates 16 and the two bolts 17, by means of which I can firmly clamp the end of the spring cover to the block 13.

The spring cover, as shown in the drawings, is, as stated above, of the type illustrated and described in the two aforesaid Leustig patents and comprises a pair of metal strips 18 and 19, one of which is intended to extend along the top of a leaf spring, and the other of which is to extend along the bottom thereof. These strips are provided with staggered overlapping tongues 19 and 20, the tongues 19 and the tongues 20 being separated from each other by suitable V-shaped notches 21, the whole construction being such that a flexible metallic cover is provided for a spring. The outer ends of the two cover plates are secured together by means of the two U-shaped clamping plates 22 and 23. The upwardly extending flanges of the clamping plate 22 are enclosed by the downwardly extending flanges of the clamping plate 23, and suitable means are provided for securing these two clamping plates together.

For alternately moving the free end of the spring cover up and down to simulate the movement of the cover while in use upon a spring, I provide certain operating or driving mechanism which is housed in the container described above, and which comprises a base plate 25 upon which is mounted the electric motor 26 having the horizontally extending shaft 27. A bracket 28 extends upwardly from the base plate 25 intermediate the ends thereof, and is provided with a horizontal bearing 29 for the shaft 30 which is secured to the shaft 27 by the coupling 31, and which forms a continuation of the shaft 27. Secured in the outer end of the section 29 is a second extension 32 of the shaft 27. The outer end of the shaft extension 32 is journaled in a bearing 32₁ carried by the bracket B. A worm 33 is secured to the outer end of the section 32 and meshes with a worm wheel 34 carried

by a vertical shaft 35, the lower end of which is journaled in the bearing boss 36 projecting from the base plate 25, and the upper end of which is journaled in a bearing 37 carried by the bracket B which projects upwardly from one end of the base plate 25.

A worm 39 is formed on the upper end of the vertical shaft 35 and drives a worm gear wheel 40 which is rotatably mounted upon a stud shaft 41 projecting from the upper end of the bracket 28, a nut 42 being used for securing the gear on the shaft 41.

The gear wheel 40 is provided with an eccentric pin 43 to which is secured the lower end of the pitman rod 44 which projects through a suitable slot 45 formed in the upper wall 5 of the container. The upper end of the pitman rod 44 is pivotally secured to a tongue 46 projecting downwardly from the clamping plate 22 by means of the pivot 47. At 48 the pitman rod is bowed outwardly to clear the projecting end of the shaft 41, and the nut 42 as the pitman passes through the dead center position opposite that illustrated in Figure 2.

An inverted U-shaped rod 50, the lower ends of which project through and are secured to the top wall 5, provides a guide-way for the free end of the spring cover which maintains the vertical alignment of the cover.

From the above description, it will be seen that when the motor 26 is supplied with current the gear wheel 40 will be driven therefrom through two worm reductions at a reduced speed, and that the pitman connection between the gear wheel 40 and the free end of the flexible spring cover will cause the free end thereof to move upwardly and downwardly in a vertical plane, thus simulating the movement and mode of operation of the flexible cover when in use.

While I have described the details of construction of a preferred embodiment of my invention, it is to be clearly understood that my invention is not limited to these details of construction, but is capable of other adaptations and modifications within the scope of the appended claims.

Having thus described my invention, what I claim is:

1. A demonstration apparatus comprising a container having a top wall, a post extending above said top wall adjacent one end thereof, an elongated flexible spring cover having one end secured to said post, said cover extending over said top wall, a motor in said container, a gear wheel driven by said motor, a pitman rod connecting the free end of said cover and an eccentric point of said gear wheel, said pitman extending through a slot in said top wall, and a guide for the free end of said cover.

2. A demonstration apparatus comprising a container having a top wall, a post extending above said top wall, an elongated flexible spring cover having one end secured to said post, said cover extending over said top wall, a motor in said container, a gear wheel driven by said motor, and a pitman rod connecting the free end of said cover and an eccentric point of said gear.

3. A demonstration apparatus comprising a flexible spring cover, means for supporting one end of said cover, motor driven means for alternately moving the free end of said spring cover in opposite directions, and a guide for confining the movement of said spring cover to a single plane.

In witness whereof, I hereunto subscribe my name this 22nd day of May, 1922.

DOUGLAS F. FESLER.
